UNITED STATES PATENT OFFICE.

IGNATZ WEISNEK, OF FEDERAL, PENNSYLVANIA.

WRENCH.

SPECIFICATION forming part of Letters Patent No. 743,359, dated November 3, 1903.

Application filed July 7, 1903. Serial No. 164,587. (No model.)

To all whom it may concern:

Be it known that I, IGNATZ WEISNEK, a citizen of the United States of America, residing at Federal, in the county of Allegheny and 5 State of Pennsylvania, have invented certain new and useful Improvements in Wrenches, of which the following is a specification, reference being had therein to the accompanying drawings.

This invention relates to certain new and useful improvements in wrenches, and relates more particularly to that type generally known in the trade as "monkey-wrenches," and the primary object of this invention is to 15 simplify the construction and facilitate the operation of the wrench with one hand.

Briefly described, the invention comprises a wrench-shank provided on one end with a rigid jaw and on its other end carrying a suitable handle. A movable jaw is slidably mounted on the wrench-shank, and within this movable jaw is a pivotally-mounted toothed dog or pawl that is under the tension of a spring and is thus normally held in engagement with teeth carried on the inner face of 20 the wrench-shank. Pivotally connected to one end of the toothed dog is a yoke which straddles the wrench-shank and has movement transverse to said shank, the outer end 25 of this yoke carrying a thumb-piece, by means of which the yoke may be operated in order to force the toothed dog away from the teeth of the wrench-shank and permit the sliding jaw to be moved to any desired position on 30 the shank. A plate is attached to the back of the sliding jaw and carries projecting fingers, which lie in back of the straps of the yoke, and thus hold the yoke in its proper position to prevent the same from falling toward the handle end of the wrench.

All of the above construction will be hereinafter more fully described, and specifically pointed out in the claim, and in describing the invention in detail reference is had to 45 the accompanying drawings, forming a part of this specification, and wherein like numerals of reference indicate like parts throughout the several views, in which—

Figure 1 is a plan view of my improved wrench. Fig. 2 is a rear elevation partly broken away. Fig. 3 is a plan view with the sliding jaw in section to show the toothed dog.

Fig. 4 is a detached detail perspective view of the operating-yoke. Fig. 5 is a like view of the plate for holding the yoke in proper position.

To put my invention into practice, I provide the wrench-shank 1, which at its outer end carries a rigid jaw 2 and at its other end is provided with a suitably-secured handle 3. 60 On the wrench-shank is mounted the slideable jaw 4, which is provided with an interior recess 5, in which is located the toothed dog 6. This toothed dog 6 has its inner end pivotally secured, as at 7, to the sliding jaw, and 65 the outer end 8 of the dog projects beyond the rear end of the slideable jaw. The teeth of the dog 6 are held normally in engagement with the teeth 8 of the wrench-shank by means of a spring 9, which bears against the dog 6, 70 as clearly seen in Fig. 3 of the drawings. The teeth 8 of the wrench-shank may be integral with the wrench-shank, or the latter may be grooved longitudinally on its inner face and a bar provided with teeth set in this groove 75 and suitably secured, the teeth of course projecting beyond the inner face of the bar. In order to operate the dog 6 so as to move the teeth thereof out of engagement with the teeth of the wrench-shank, I provide a yoke 10, 80 which straddles the wrench-shank 1 and is bifurcated or split at one end to receive therein the end 8 of the dog, which is pivotally secured in position. The other end of this yoke is provided with a thumb-piece 11, which lies directly over the back of the wrench-shank 1 and is preferably knurled, as seen in Figs. 2 and 4 of the drawings. Attached to the slideable jaw 4 by means of a screw 12 or in any other suitable manner is a plate 14, which has 90 projecting fingers 15 to engage in back of the side straps of the yoke 10, as clearly seen in Fig. 1 of the drawings, thus preventing the yoke from moving toward the handle end of the wrench. The thumb-piece 11 projects 95 rearwardly beyond the plate 14, as seen in Figs. 1, 2, and 3, whereby it may be readily engaged by the operator.

To operate the wrench, it will be apparent that it is only necessary to depress the thumb-piece 11 toward the wrench-shank in order to cause the yoke 10 to move the dog 6 in a manner to disengage its teeth from the teeth of the wrench-shank and allow the shifting

of the slidable jaw into any desired position upon the wrench-shank. As soon as pressure on the thumb-piece 11 is removed the spring 9 will force the teeth of the dog into engagement with the teeth of the wrench-shank and hold the slidable jaw in the adjusted position.

It will be apparent that when the yoke is depressed and the dog thus disengaged the operator may move the slidable jaw by the aid of the thumb with which he depresses the yoke either toward the rigid jaw or away from the same in order to give the desired space between the two jaws.

Although in the present illustration I have shown the teeth of the dog and those of the wrench-shank as both being "straight-cut" teeth, it will be apparent that if the teeth of the wrench-shank are made inclined toward the rigid jaw the adjustment of the slidable jaw would be obtained without requiring the depressing of the yoke 10, only necessitating the depressing of the yoke and the consequent disengagement of the dog when it was desired to move the slidable jaw toward the handle end of the wrench.

It will be noted that various changes may be made in the details of construction with-

out departing from the general spirit of my invention.

Having fully described my invention, what I claim as new, and desire to secure by Letters Patent, is—

In a wrench, the combination with a wrench-shank having teeth on its inner face and provided at its outer end with a rigid jaw, of a slidable jaw mounted on the wrench-shank and provided with a recess, a toothed dog pivotally mounted in said recess with its rear end projecting beyond the slidable jaw, a spring normally holding said toothed dog in engagement with the teeth of the wrench-shank, a yoke straddling the wrench-shank and pivotally connected to the extending end of the toothed dog, a thumb-piece carried by said yoke, and a plate secured to the slidable jaw and provided with inwardly-projecting fingers engaging the yoke to hold the latter in position, substantially as described.

In testimony whereof I affix my signature in the presence of two witnesses.

IGNATZ WEISNEK.
